US00D740636S

(12) **United States Design Patent**
Koeniger

(10) **Patent No.:** **US D740,636 S**
(45) **Date of Patent:** **** Oct. 13, 2015**

(54) **BREAKER**

(71) Applicant: **Hilti Aktiengesellschaft**, Schaan (LI)

(72) Inventor: **Tobias Koeniger**, Bregenz (AT)

(73) Assignee: **Hilti Aktiengesellschaft**, Schaan (LI)

(**) Term: **14 Years**

(21) Appl. No.: **29/478,282**

(22) Filed: **Jan. 3, 2014**

(30) **Foreign Application Priority Data**

Jul. 5, 2013 (WO) DM/081 434

(51) **LOC (10) Cl.** **08-03**

(52) **U.S. Cl.**

USPC **D8/69**

(58) **Field of Classification Search**

USPC D8/14.1, 61–70; 81/429, 454–456, 469,
